UNITED STATES PATENT OFFICE.

CHARLES EDWARD HAVILAND, OF LIMOGES, FRANCE.

DESIGN FOR A COVER-DISH.

SPECIFICATION forming part of Design No. 23,149, dated March 27, 1894.

Application filed March 1, 1894. Serial No. 501,999. Term of patent 14 years.

To all whom it may concern:

Be it known that I, CHARLES EDWARD HAVILAND, a citizen of the United States, residing at the city of Limoges, in the Republic of France, have invented and produced a new and original Design for a Cover-Dish and other Articles, of which the following is a specification, reference being had to the accompanying drawings forming part thereof, and in which—

Figure 1 is a top view of a cover-dish bearing and incorporating my design. Fig. 2 is a side elevation of same; and Fig. 3 is a vertical section of same on the dotted line 3—3 of Fig. 1.

The leading features of my design consist of the ornamental form and configuration of the dish and the surface ornamentation thereon, substantially as illustrated in the accompanying drawings.

The sides of the body of the dish are composed of the scalloped sections A and are slightly concave along their upper portions, whence they extend downward and outward to a point or line at which they rather abruptly turn inward and downward to the base B, which forms ornamental feet C and bears the ornate scroll figures D. The sides of the body of the dish at the points of the depressions between the scalloped sections A bear the ornamental scroll figures E in relief, and between the lower ends of said figures E and

running along the line at which the lower part of the sides of the body turn inward toward the base B are the ornate scroll figures 35 F, G, while between the scroll figures E and the end handles H are the ornamental scrolls I. The handles H at their edges have the form of ornate scrolls.

The cover, lettered J, has at its raised center the handle K, and at its outer portion the series of scalloped sections L, corresponding with the sections A of the body of the dish, while the edge of the rim of the cover J is composed of the series of small scallops *a* having between them the raised tapering portions *b*. Upon the cover J at the points between the sections L thereof are the ornamental scroll figures M in relief, which, correspond with the scroll figures E on the sides of the body of the dish; and intermediate the inner ends of said figures M and the ends of the handle K are the ornamental scroll figures *d, e, f* as shown. 40 45 50

What I claim is—

The design for a cover-dish and other articles, substantially as shown and described.

Signed at the city of Limoges, in the Republic of France, this 15th day of February, A. D. 1894.

CHARLES EDWARD HAVILAND.
